UNITED STATES PATENT OFFICE.

LAURENCE R. BARGHAUSEN AND CESARE L. CONSTANTINI, OF WASHINGTON,
DISTRICT OF COLUMBIA.

SALIVA-EJECTOR.

1,053,965.

Specification of Letters Patent. Patented Feb. 25, 1913.

Application filed December 11, 1912. Serial No. 736,223.

To all whom it may concern:

Be it known that we, LAURENCE R. BARGHAUSEN and CESARE L. CONSTANTINI, citizens of the United States, residing at Washington, in the District of Columbia, have invented certain new and useful Improvements in Saliva-Ejectors; and we do hereby declare the following to be a full, clear, and exact description of the invention, such as 10 will enable others skilled in the art to which it appertains to make and use the same.

This invention relates to certain novel and useful improvements in saliva ejectors.

In carrying out our invention it is our purpose to provide a simple and efficient form 15 of saliva ejector designed to be inserted in the mouth of the patient in such manner as to drain off or remove the saliva and at the same time enable the dentist to use both 20 hands while working on the teeth.

A further object of our invention is to provide a device of this character which may be used in the mouth of the patient without causing discomfort or injuring the tissues of 25 the mouth and gums.

With the above recited objects and others of a similar nature in view, our invention consists in the construction, combination and arrangement of parts set forth in and 30 falling within the scope of the appended claim.

In the accompanying drawings: Figure 1 is a perspective view of the saliva ejector embodying our invention. Fig. 2 is a view 35 in side elevation. Fig. 3 is an end view looking from the rear toward the front of the device. Fig. 4 is a cross sectional view taken through the saliva apertures of the ejector.

40 In the present instance, we so construct our device that it embodies a tubular stem or shank portion designed to be attached at its lower end to a tube of rubber or the like, which in turn is connected with the usual 45 water suction pump so as to remove the accumulated saliva and water from the mouth of the patient through the ejector. The upper end of this shank is curved or bent and carries a tubular horizontally extending 50 U-shaped member adapted to lie within the mouth of the patient beneath the tongue and of sufficient width to embrace the latter, this U-shaped member, when in use, occupying a position beneath the tongue and between 55 the latter and the alveolar processes. The

branches of this U-shaped member extend rearward in the mouth adjacent to the saliva glands and ducts. The branches or arms of the U-shaped member are each provided with upwardly and outwardly flared plate 60 sections rigidly attached at their lower portions to the inner sides of the branches or arms, these plates being tapered toward the front or center portion of the U-shaped member so that at the point where the 65 shank or stem joins such member the forward ends of the plates are flush with or slightly below the upper plane of the member, as is clearly shown in the drawings. The branches of the U-shaped member are 70 provided with apertures or openings formed in the upper surfaces of such branches adjacent the rear closed free ends of the latter. By such an arrangement the accumulation of the saliva and water passes along the 75 grooves or channels formed by the outer surface of the plate and the branches of the U-shaped member and such accumulation is then drawn through the apertures out through the stem of the ejector. Furthermore, it will be noted that the soft tissues of the tongue and mouth will not prevent the working of the ejector. That is, these soft tissues will not be drawn into and stop up the apertures so as to prevent the proper 80 working of the instrument for the reason that the plates fixed on the branches of the U-shaped member prevent the tissues being drawn into the openings and at the same time they hold the tongue out of the way so 85 it will not interfere with the dentist's work. Referring now to the accompanying drawings in detail, the numeral 1 designates a tubular shank or stem which extends vertically when the device is in operative position, this stem being formed of any suitable material and is adapted to have attached at its lower end 2 a rubber tube or pipe, which it is not deemed necessary to show, as it is of an ordinary construction. The upper end 90 portion of the stem or shank is curved rearwardly at 3 and is approximately semi-circular in form so that when the device is in use the upper curved end of the shank extends over the lower lip and front teeth of 95 the patient. The end of this curved shank merges into and communicates with the horizontally disposed rearwardly extending U-shaped member 4 which is also tubular in form and has the free ends of the arms pref- 100 105 110

erably closed as at 5. This U-shaped member is designed to lie beneath the tongue and is sufficiently wide to embrace the latter. The top portion of each branch or arm 6 is 5 perforated as at 7 to form an inlet for the saliva and water into the branch or arm, this perforation or opening being preferably located adjacent the closed free end of the arm. To the inner side of each arm is 10 fixedly attached, such as by brazing or the like, a plate 8 which is preferably formed of metal. Each of these plates is flared upwardly and outwardly, as shown at 9 and the top edge of each plate is cut or inclined 15 forwardly and downwardly until the front or meeting ends of the plates lie substantially flush with or below the central portion of the U-shaped member. By this construction of the plates, a rest or support for 20 the tongue is formed, the tongue lying on and between the plates, while at the same time curved grooves or channels 10 are formed by the outer lower portion of each plate and the adjacent upper and inner portion 25 of each branch or arm of the U-shaped member. Along these channels the dropping saliva and water will flow to the perforations through which said saliva and water may be drained by suction through 30 the stem and rubber tube to the point of discharge.

We are aware of the fact that it has been proposed to construct saliva ejectors of this type, as is exemplified in the patents to J. B. 35 Jordan, 730,128, dated June 2, 1903 and 951,130, dated March 8, 1910. But so far as we are aware, we are the first to provide a saliva ejector in which the horizontally disposed U-shaped members lie entirely beneath the tongue and inside the teeth with 40 the tongue embraced by and resting upon

the plates, the latter being disposed and correlated relative to the U-shaped member within the mouth in such manner that channels are formed between the lower outer portions of the plates and the adjacent surfaces of the branches of the U-shaped member so that the accumulated water and saliva will flow along said channels to the openings in the upper rear portions of the branches 50 through which openings said water and saliva may be drained through the ejector to the point of discharge.

It is, of course, to be understood that our 55 ejector may be made of any suitable material and that modifications and changes may be made in the details of construction without departing from the spirit of the invention or exceeding the scope of the claim.

What we claim is:

A saliva ejector comprising a tubular shank terminating at its upper end in a rearwardly curved portion, a horizontally disposed U-shaped tubular member communicating with the curved end portion of the shank and of sufficient width to embrace the tongue, the branches of said U-shaped member extending rearwardly, the ends of said branches being closed, said branches having openings in the upper rear portions thereof, and an upwardly and outwardly flared plate fixedly attached to each branch and forming channels in conjunction with the adjacent portions of the branches, which channels lead to the openings in the branches.

In testimony whereof, we affix our signatures in the presence of two witnesses.

LAURENCE R. BARGHAUSEN.
CESARE L. CONSTANTINI.
